Eugene Bark

UNITED STATES PATENT OFFICE.

JAMES FEUERLICHT, OF NEW YORK, N. Y.

DESIGN FOR A DOLL.

55,942.

Specification for Design.

Patented Aug. 3, 1920.

Application filed February 25, 1920. Serial No. 361,271. Term of patent 3½ years.

To all whom it may concern:

Be it known that I, JAMES FEUERLICHT, a citizen of the United States, residing in the city, county, and State of New York, have invented a new, original, and ornamental Design for a Doll, of which the following is a specification, reference being had to the accompanying drawing, forming a part thereof.

The figure is a perspective view of a doll, showing my new design.

I claim

The ornamental design for a doll as shown.

JAMES FEUERLICHT.
